UNITED STATES PATENT OFFICE.

JOHN ERNEST KENNEDY, OF MONTREAL, CANADA.

WARDROBE.

SPECIFICATION forming part of Letters Patent No. 631,525, dated August 22, 1899.

Application filed June 23, 1898. Serial No. 684,314. (No model.)

To all whom it may concern:

Be it known that I, JOHN ERNEST KENNEDY, merchant, of the city of Montreal, in the county of Hochelaga, in the Province of Quebec, Canada, have invented certain new and useful Improvements in Wardrobes, of which the following is a specification.

My invention relates to improvements in wardrobes; and the object of the invention is to design a form of wardrobe more particularly applicable for stores for ready-made garments, whereby storage-space may be economized, classification of size and price facilitated, and time saved in selling and handling the goods; and it consists, essentially, of a wardrobe each section of which is provided with extension tubes or rods, the uppermost of each set being carried by the frame and the lower being suspended by suitable carriers from the upper tube.

Figure 1 is a sectional perspective view of portion of a wardrobe-case constructed in accordance with my invention, showing the extensible rods in position in the wardrobe and the door closed. Fig. 2 is a similar view showing the door open and the extensible rods drawn forth. Fig. 3 is an enlarged view of the extensible rods.

In the drawings like letters of reference indicate corresponding parts in each figure.

A is the top of the wardrobe, B the back, and C the front upright separating the doors of the wardrobe.

D is the front top board, and E the door.

F is the top tube, which is supported on the back B by the bracket G, the end of which extends into the tube, and on the top front board by the bracket H, which extends into the tube.

F' is the tube situated next below the tube F and supported thereon by the carrier-brackets I and I', which are suitably brazed or otherwise connected to the lower tube F'. The bracket I is preferably provided with grooved rollers *i*, journaled therein at the top and bottom of the tube F. The bracket I' is provided with a single grooved roller *i'*, resting on the tube F.

F² is the undermost tube, which is provided with carrier-brackets J J', suitably secured at

the bottom to the tube F². The bracket J has journaled in it at the top suitable rollers *j*, which are designed to run on the tube F'. The bracket J' has suitably journaled in it at the top the grooved roller *j'*, which is designed to run upon the tube F'. The end of the tube F' is provided with a stop-collar and handle *f*, and the end of the tube F² has secured to it a stop-collar *f'*.

It will be noticed on reference to Fig. 3 that when the tubes are extended the bracket I' and roller thereon are stopped by the bracket II and the bracket J' and roller are stopped by the stop-collar *f*, so that when the tubes are extended out to their fullest extent the tube F² is practically entirely outside the compartment of the wardrobe altogether. Such tube F² is designed to receive and hold suitable garment-supporters, from which a number of garments may be hung.

What I claim as my invention is—

1. The combination with the wardrobe, of a tube or rod having fixed supports for the same in the frame of the wardrobe above the level of the door or opening, a second tube depending from the fixed tube and having the outer end free, and supported at the inner end and intermediately of its length by depending brackets from the fixed tube, so that it may be slid out approximately half its length beyond the outer end of the fixed tube, and a third tube depending from the second tube and having its outer end free and supports at its inner end and intermediate of its length connected to the second tube whereby it may be slid out approximately half its length and substantially beyond the end of the fixed tube and front of the wardrobe as specified.

2. The combination with the wardrobe, of a tube or rod having fixed supports for the same in the frame of the wardrobe above the level of the door or opening, a second tube having a bracket and rollers at the inner end by which it is supported from the fixed tube, and the outer free end provided with the laterally-extending stop, a third tube having a bracket secured to the inner end and rollers journaled in same by which it is supported at the inner end outside the bracket on the sec-

ond tube and a stop at the outer free end, the intermediate bracket secured to the lowermost tube and having an upward extension and roller supported on the second tube and 5 a further upward extension supported on the fixed tube whereby the tubes are supported in their closed position and supported, braced

and held together in their drawn position as specified.

JOHN ERNEST KENNEDY.
